UNITED STATES PATENT OFFICE.

DANIEL O. BERRY, OF CHICAGO, ILLINOIS.

FURNACE.

1,213,146.

Specification of Letters Patent. Patented Jan. 23, 1917.

Application filed March 25, 1916. Serial No. 86,544.

To all whom it may concern:

Be it known that I, DANIEL O. BERRY, a citizen of the United States, residing at Chicago, Cook county, State of Illinois, have 5 invented certain new and useful Improvements in Furnaces, of which the following, taken in connection with the drawings, is a description.

My invention relates to smoke-consuming 10 furnaces using high or low pressure boilers, and has for its object the production of a furnace designed to more completely utilize all of the products of combustion, thereby greatly reducing the cost of operating 15 furnaces of this class.

A further object of my invention is to provide means for introducing hot-air within 20 the fire chamber to combine with the gases rising from the grate, which in many of the boilers and furnaces as now constructed 25 is wasted. I accomplish this object by returning a part of the products of combustion which have been only partially consumed, from a chamber at the rear of the 30 boiler, through an opening in the bridge wall to a compartment in which there is a zone of more complete combustion, where the gases are united with other gases passing from the fire box containing an excess 35 of oxygen with which they are united and finally consumed. The mixture of the current returning from the combustion chamber at the rear of the boiler with a current of highly heated gas and air passing from 40 the fire box over the bridge wall, thoroughly consumes every part of the material not previously oxidized.

In the accompanying drawings, I have 45 illustrated what I now consider the preferred form of my invention, although changes may be made in the proportion and minor details of construction without departing from the spirit of my invention, in which—

Figure 1 is a vertical, longitudinal, sectional view of a furnace and boiler embodying my invention; Fig. 2 is a vertical, transverse, sectional view, taken on line 2—2 of Fig. 1, looking in the direction of the arrow; 50 Fig. 3 is a horizontal, sectional view, taken

on line 3—3 of Fig. 1; Fig. 4 is a detail of the air-distributing pipe, taken on line 4—4 of Fig. 3.

In carrying out my invention, A represents a furnace, and B a flue boiler, which 55 may be either a high or low-pressure structure.

B' is the fire box, C the grate, C' the ash pit, C² the water jacket, all of which are of the usual form of construction, and will be 60 readily understood by those familiar with the art. Entrance to the grate and to the ash pit is effected through the openings b, c, which are closed by doors b', c', of the usual furnace construction.

D is the bridge wall, which extends nearly to the crown sheet d, leaving a passageway d', between the top of said wall and the crown sheet.

d² is a ledge or shoulder formed in the 70 bridge wall and upon which one end of the grate bars C, rests. That part of the bridge wall, D', which extends above the ledge d², is inclined toward the front of the furnace, as shown more clearly in Fig. 1. This part 75 of the bridge wall, D', is hollow, having an air-induction passageway, D², therein, which is provided with an inlet opening e, at the bottom thereof and outlet openings e', at the top thereof. A wall E extends transversely 80 of the furnace between the upper portion of the bridge wall D' and the boiler B, forming an opening or compartment E', between the wall E and the upper portion of the bridge wall D', and a compartment 85 E² between the wall E and the boiler flues B². The compartment E' extends downwardly into the bridge wall D to the clean-out opening e² at the bottom thereof. The transverse wall E rises from the rear 90 portion of the bridge wall D to the crown sheet, and is provided with an opening e³, therethrough, at a point level with the bottom of the boiler casing B.

F is a secondary combustion chamber at 95 the rear of and beneath the boiler through which the gases and products of combustion travel on the way to the exit opening.

G is a passageway through the rear of the bridge wall from the chamber F, which pas- 100

sageway extends upwardly in the bridge wall and opens into the compartment E^2 , between the transversely-extending wall E to the boiler tubes B^2 . Air ducts F' , F^2 , extend through the furnace wall at each side thereof entering the bridge wall and extending upwardly at each side of the fire box nearly to the top of the hollow portion of the bridge wall D' . Said ducts, F' , F^2 , are 5 in communication with an air pipe F^3 , which extends horizontally across the upper portion of the fire box (shown more clearly in Fig. 3). The pipe F^3 , extends through the fire box B' , in the form of a rectangular 10 frame, and is provided upon the forward end thereof with an elongated opening f , upon the inside of said frame. Air entering the ducts F' , F^2 , rises through the passageway in the wall upon each side of the furnace to the pipe F^3 , where it is superheated, 15 and discharges through the opening f , in the fire chamber B' , where it mingles with the products of combustion rising in the fire chamber. Through the ash pit C' , superheated air also enters the air induction passage D^2 , through the opening e , and is discharged into the fire chamber through the 20 openings e' , e' . From the drawings it will be observed that there are two currents of air discharging into the fire chamber, one through the opening f in the pipe F^3 , and the other through the openings e' coming through the passageway D^2 . The confluence of these two currents results in a thorough 25 intermingling of the oxygen with the products of combustion before passing over the bridge wall.

The operation of the device is as follows: 30 The products of combustion rising in the fire box B' , enter a zone of complete combustion created by the accession of the air currents flowing into said chamber from the openings e' and f . From this chamber, said combustion products pass over the forwardly-inclined wall D' , through the opening between the top of said wall and the crown sheet d , into a compartment between said wall and the transversely-extending wall E ; thence downwardly through the 35 opening e^3 in said wall to the compartment E^2 ; thence through the passageways between the boiler pipes to the rear combustion chamber F , at the rear of and beneath the boiler B . The lighter gases will then 40 travel in the general direction of the draft toward the stack, the heavier gases will return toward the opening G in the bridge wall where they pass upwardly into the compartment E^2 , uniting with the fresh 45 products of combustion coming from the fire chamber, where by reason of the air currents heretofore described, it is supplied with an excess of oxygen, more than is necessary to completely oxidize unconsumed

products carried with it, thereby carrying 65 sufficient oxygen to oxidize the products of combustion uniting therewith from the rear combustion chamber in the compartment E^2 . The result of this action is that the products of combustion are so completely consumed 70 that practically no smoke escapes through the stack to atmosphere. The force of the currents of air entering the fire chamber from opposite directions through the openings f and e' , causes a very thorough mixing 75 of the oxygen with the products of combustion, so that as said combustion products leave the fire chamber they carry an excess of oxygen which is sufficient to reoxidize the heavier gases returning from the rear or 80 secondary combustion chamber.

I claim:

1. The combination with a furnace provided with a fire box and grate, of a bridge wall having a portion thereof extending 85 nearly to the crown sheet of the furnace and inclined forward from the grate to the top thereof, said wall being provided with air inlet ducts, a transversely-extending wall between the first named wall and the furnace boiler, forming a compartment between 90 said wall and the boiler and between said wall and the inclined wall, a pipe communicating with said air ducts and extending horizontally across the upper portion of the 95 fire box toward the front wall thereof, said horizontal pipe having an elongated opening on one side inside of the fire box, substantially as described.

2. In a furnace provided with a fire box 100 and grate, the combination of a bridge wall having a forwardly-inclined wall rising nearly to the crown sheet of the furnace, and a second wall rising to the crown sheet and having an opening through the same above 105 the bridge wall, the forwardly-inclined wall being provided with air ducts extending nearly to the top of the fire chamber, an air pipe connecting therewith and extending into the fire chamber with a discharge opening near the front wall of the furnace, the forwardly-inclined wall being provided with 110 an air induction passageway opening from the furnace ash pit and discharging superheated air into the fire chamber opposite the discharge opening from the air pipe, and means for creating a draft through said furnace to carry the products of combustion through the boiler, substantially as described.

3. In a furnace provided with an air chamber and grate, a bridge wall having two partition walls rising therefrom with openings therethrough, a boiler having a combustion chamber at the rear and bottom 125 thereof, the wall of the furnace having air ducts through the sides thereof which open into the fire chamber discharging super-

heated air toward the rear thereof, one of the bridge wall partitions having air induction passages discharging superheated air toward the front of the fire chamber, means and means for reoxidizing the heavier gases after they leave the last combustion chamber, substantially as described.

5 for creating a draft through said furnace to carry the products of combustion through the boiler to the rear combustion chamber, In testimony whereof I have signed this specification.

DANIEL O. BERRY.
